CALIFORNIA.

DIRECTION-INDICATOR.

1,246,979

Specification of Letters Patent. Patented Nov. 20, 1917.

Application filed September 16, 1916. Serial No. 120,556.

To all whom it may concern:

Be it known that we, LEON S. MOORHEAD and MAURICE G. BLAIR, citizens of the United States, residing, respectively, at Los Angeles, in the county of Los Angeles, State of California, and Eureka, in the county of Humboldt and State of California, have invented a new and useful Direction-Indicator, of which the following is a specification.

10 The primary object of this invention is to provide a vehicle direction indicating device which may be operated by the driver of the vehicle to indicate to approaching and following vehicles, also pedestrians, whether or 15 not a right or left turn is to be made, and the invention resides in the provision of a device of this character which is simple in construction, reliable in operation and inexpensive to manufacture.

20 Another object of this invention is to provide a novel form of indicating device which is operated by a motor controlled from the driver's seat of the vehicle and rotates in opposite directions to indicate contemplated movements of the vehicle, the device being so constructed that the contemplated movement will be indicated by word and the pointing of the indicating member in the direction corresponding to the contemplated movement.

25 In the drawings:

Figure 1 represents a front elevation of the device;

Fig. 2 a front elevation showing the device in indicating position;

Fig. 3 a horizontal sectional view taken on line 3—3, Fig. 1, and

Fig. 4 a diagrammatic view showing the electrical circuit for the device.

30 In the drawings, in which like parts are designated by like characters of reference throughout the several views, 1 designates a casing of any suitable construction which houses the working parts of the device and 35 is rounded upon its upper side, the balance of the casing being substantially rectangular in outline. A suitable electrical motor 2 is mounted upon the bottom wall 3 of the casing 1, and has a shaft 4 which projects 40 through the front wall of the casing 1. Fixed to the outer end of the shaft and spaced 45 from the wall 5 of the casing is a circular indicating member 6 in the form of a disk, which is of slightly less diameter than the 50 casing. It will be noted that the rounded 55

upper end of the casing is concentric with the disk and this provides for the conformity of outline and a pleasing, neat appearance of the device as a whole.

60 A pointer projection 7 is preferably formed integral with the disk 6 and extends outwardly from the periphery thereof, the pointer 7 being shaped to correspond to the head of an arrow and extended for approximately its whole length beyond the casing. 65 Secured to the disk 6 at a point near the periphery thereof and directly opposite the projection 7 is a weight 8 which serves to hold the pointer projection 7 in upright position normally. Formed in the disk 6 and 70 in line with the weight and projection 7 is an elongated opening or slot 9, preferably of rectangular outline which is adapted to register, upon operation of the device, with the designations "Left" and "Right" indicated at 10 and 11, said designations being printed or otherwise applied to the wall 5 on opposite sides thereof.

75 The opening or slot 10 is elongated from the point near the projection 7 toward the center of the disk, that is, its longitudinal axis is in line with the longitudinal axis of the pointer or projection, so that the words "Left" and "Right" and the other character will be clearly revealed.

80 In order to provide for the registration of the opening 9 with the designations 10 and 11, stop members 12 are mounted upon opposite sides of the casing and arranged to engage the projection 7 to limit the movement of the projection to horizontal in either direction.

85 The electrical circuit for the motor 2 comprises a battery or other source of current 13, extending from one side of which is a conductor 14, which terminates in a contact point 15. From the other side of the battery 90 a conductor 16 leads and terminates in a contact point 17.

95 A double switch 18 of any suitable character and normally held open by spring means 19 has its insulated blades connected with the conductors 20 and 21 which are connected to the field 22 of the motor and the motor itself. Upon the closing of the 105 switch 18 the motor will rotate for example in a clockwise direction, the direction of flow of the current in this instance being indicated by arrows located along the conductors 14—20.

- The reversing circuit comprises conductors 23 and 24 which are connected with the conductors 14-16 respectively and terminate in contact points 25 and 26. A double switch 27 having connection with the conductors 28 and 29 is adapted for co-operation with the contacts 25 and 26, the conductors 28 and 29 being respectively connected with the motor and field 22 thereof.
- 10 The switches 18 and 27 may be located wherever desired, but must be within reach of the driver of the vehicle and when the switch 18 is closed the current flows from the positive side of the source of current 13 through conductor 14, switch 18, conductor 20, field 22, motor 2, conductor 21, switch 18, and conductor 16, back to the negative side of the battery. This provides for the operation of the motor in one direction, for example, the disk 6 will be turned to the left as indicated in Fig. 2 of the drawings. The turning of the disk 6 to the left causes the opening 9 to register with the designation 10 and reveal the word "Left" on the wall 5 of the casing. The direction of movement of the vehicle is also indicated by the projection 7, which at this time points to the left. The stop 12 on the left hand side of the casing limits the movement of the disk 6. When the switch 27 is closed, current flows from the positive side of the source of current 13 through the conductor 23, conductor 29, motor 2, field 22, conductor 28 and conductors 24 and 16 to the negative side of the battery. This causes the reversal of the direction of flow of current through the field 22 and the motor is turned in the opposite direction, bringing the pointer 6 to the right hand side of the casing and revealing the designation "Right."
- 15 The indicating member will be held in indicating position as long as the switch for operating the device is closed, and upon the opening of the switch the weight 8 causes 45 the indicator to return to normal position

and the pointer to be held in upright position. If desired, a suitable character, for instance, a question mark such as shown in the drawings, may be provided upon the wall 5 in such location that it will register with the opening 9 when the device is in normal position.

With reference to the foregoing description and accompanying drawings, it is seen that we have provided a direction indicator for vehicles which will operate so as to attract the attention of autoists and pedestrians with sufficient surety to be highly effective in performing the function of indicating to such autoists or pedestrians the contemplated movements of the vehicle to which it is attached.

What we claim is:

A direction indicator for vehicles comprising a casing, a circular disk mounted for rotation exteriorly of the casing, means within the casing to rotate the disk, said casing having the words "Left" and "Right" appearing thereon, said disk having a projection extending from the periphery thereof and being provided with an elongated opening having its longitudinal axis in line with the longitudinal axis of the projection whereby when the disk is rotated the opening will register with the words "Left" and "Right" on the casing and reveal said words, a weight member secured to the disk at a point directly opposite to the projection to normally hold the disk with the projection pointed upwardly, and means to limit the movement of the disk in either direction.

Signed at Los Angeles, California, this 2nd day of September 1916.

LEON S. MOORHEAD.
MAURICE G. BLAIR.

Witnesses as to signature of Maurice G. Blair:

W. ERNEST DICKSON,
GRACE MULFORD.
